US0D1082370S

(12) **United States Design Patent** (10) **Patent No.:** **US D1,082,370 S**
(45) **Date of Patent:** **** Jul. 8, 2025**

(54) **PERSONAL CARE ARTICLE HOLDER**

(71) Applicant: **The Gillette Company LLC**, Boston, MA (US)

(72) Inventors: **Christopher Ramm**, North Attleboro, MA (US); **Morgan Elizabeth Matt**, Boston, MA (US)

(73) Assignee: **The Gillette Company LLC**, Boston, MA (US)

(**) Term: **15 Years**

(21) Appl. No.: **29/893,000**

(22) Filed: **May 24, 2023**

(51) LOC (15) Cl. **28-03**

(52) U.S. Cl.

(57) **CLAIM**

The ornamental design for a personal care article holder as shown and described.

DESCRIPTION

FIG. 1 is a front perspective view of a personal care article holder showing our new design;

FIG. 2 is a front view thereof;

FIG. 3 is a rear view thereof;

FIG. 4 is a right view thereof;

FIG. 5 is a left view thereof;

FIG. 6 is a top view thereof;

FIG. 7 is a bottom view thereof; and,

FIG. 8 is a rear perspective view thereof.

The broken lines show portions of the personal care article holder that form no part of the claimed design.

1 Claim, 8 Drawing Sheets
